UNITED STATES PATENT OFFICE.

ETHAN N. HESCOCK, OF NEW YORK, N. Y., ASSIGNOR TO NEW JERSEY FOUNDRY & MACHINE COMPANY, A CORPORATION OF NEW JERSEY.

ADJUSTABLE TROLLEY.

1,179,430.

Specification of Letters Patent. Patented Apr. 18, 1916.

Application filed June 25, 1915. Serial No. 36,224.

To all whom it may concern:

Be it known that I, ETHAN N. HESCOCK, a citizen of the United States, and a resident of the borough of Brooklyn, city and 5 State of New York, have invented certain new and useful Improvements in Adjustable Trolleys, of which the following is a specification, taken in connection with the accompanying drawing, which forms a part 10 of the same.

My invention relates to a trolley of any description for carrying weights and which runs upon an elevated track. These tracks are formed by the flanges of I-beams, channel irons, T-rails, or other structures. The 15 width of these flanges vary dependent upon the weight per foot of the I-beam, channel iron, T-rail or other track. In the factories, and other locations, where such elevated tracks are used, it is necessary that the tracks be installed to meet the heaviest load and for the heaviest trolley, or other member, which may be mounted to turn upon them. On these identical tracks, however, 20 it is often desirable to operate a light trolley to do comparatively light work.

My invention relates to a trolley of any capacity, whether geared or not being immaterial, so as to adapt that trolley, by 25 means of a slight adjustment which can be made by unskilled labor, to operate upon the tracks of an I-beam, channel iron, T-rail or other track of any size or form, the accompanying drawing showing several 30 illustrative embodiments of my invention and in which the same reference numerals refer to similar parts and several figures;

Figure 1 is a transverse vertical section through an I-beam, and a portion of my 35 improved trolley; Fig. 2 is a side elevation of my trolley mounted upon an I-beam; Fig. 3 is a fragmentary end elevation of the trolley shown in Fig. 1 and Fig. 2; Fig. 4 is a fragmentary detail vertical section 40 showing one form of locking member; Fig. 5 is a view of a modification, partly in plan and partly in section; Fig. 6 is a transverse vertical section on the line 6—6 of Fig. 5; Fig. 7 is a fragmentary detail view, partly 45 in end elevation and partly in vertical section, showing a modification.

In the illustrative embodiments of my invention shown in the drawings 1 is an I-beam, but of course it is to be understood 50 that it might be a channel iron, T-rail or

any other similar form of track. The flange 2 forms a track the width of which will vary with the weight per foot of the I-beam, channel iron, T-rail or other track used. Upon this track 2, I mount my trolley 3 60 which is shown in the simplest form, as an ungeared trolley, having side plates 4 and 5 on which are mounted the studs 6 and 7 each of which is provided with a head 8 and with a screw threaded shank 9, to coöperate 65 with a nut 10 to securely hold the traction wheels 11, 11 upon the headed studs.

The lower ends of the plate 4 and 5 are secured together by means of a connecting member 12, preferably in the form of a pin 70 which may be provided with a head 33 and upon which is mounted the ring 32, or other load supporting member. This pin 12 passes through the cheek plates 13 which, for economy in manufacture, are preferably 75 formed separate from the side plates 3 and 4 and are then secured to them by any suitable means as by the rivets 14, 14 or bolts 15.

One or both ends of the connecting member or pin 12 is provided with integral means which, coöperating with a locking member carried by the cheek plates 13, or side plates 3 or 4, as the case may be, will permit quick adjustment of the traction 85 wheels 11, 11 to and from each other, to fit different widths of flanges 2. This adjustment may be made in different ways. In Figs. 1 to 4 I have shown one end of the pin 12 formed with a plurality of parallel 90 grooves 16 which may be stamped, swaged, cut or otherwise formed in the pin 12. In these figures I have shown a locking member 17 in the form of a screw having a smooth inner end 18, the screwthreaded 95 portion of the locking member 17 coöperating with female screw threads in the cheek plate 13 carried by the side plate 4. It is obvious that by unscrewing the screw 17 until the smooth portion 18 is brought 100 out of engagement with the particular groove 16, which it may have engaged, that the side plate 4 may be adjusted to or from the side plate 3 and at the same time bring the traction wheels 11, 11 to or from each 105 other so that they will fit the particular width of flange or track 2 with which it may be desired to coöperate. Having obtained the necessary adjustment for that particular size flange, the screw 17, by means of 110

an ordinary screw driver, is screwed back into the cheek 13 when the smooth portion 18 will engage in another groove 16 and lock the parts in their new adjusted position.

In some cases I may, to get a finer adjustment, form the pin or connecting member 19 with the grooves 20, 20, 21, 21 and 31, 31, staggered with relation to each other. That 10 is a partial rotation and longitudinal movement of the connecting member or pin 19 will insure an intermediate or finer adjustment than the series of parallel grooves 16 shown in Figs. 1 to 4 inclusive. I may also, 15 in some cases, provide both ends of the connecting member or pin with integral adjusting means which, as shown in Fig. 5, are the staggered grooves previously described. In such a trolley I would use two locking 20 screws 22, shown in dotted lines in Fig. 5. In some cases I may form a connecting member 23 with indentations 24, 24, 25, 25, and 26, 26 which are preferably arranged in staggered relation to each other, and with 25 which coöperates a removable pawl or dog 27, held in position by a bolt 28 screwing into the side plate 4. These indentations may be formed in the connecting member 23 in any suitable manner as by being 30 stamped or otherwise formed.

It is clear that in all forms of my invention, quick adjustment can be made of the trolley 3 to fit any particular width of track 2 and that this adjustment can be made by 35 unskilled workmen with a minimum waste of time and labor.

Having thus described this invention in connection with several illustrative embodiments thereof to the details of which I do 40 not desire to be limited, what is claimed as new and what it is desired to secure by Letters Patent is set forth in the appended claims:

1. In a trolley the combination of a plurality of side plates, traction means carried 45 by the side plates, a member connecting the side plates and integral adjusting means forming a part of the connecting member, and one or more locking members carried by 50 the side plates adapted to coöperate with the integral adjusting means to adjust the trolley to different sized tracks.

2. In a trolley the combination of a plurality of side plates, traction means carried 55 by the side plates, a member connecting the side plates and integral adjusting means forming a part of the connecting member, and a locking member carried by the side plates adapted to move at an angle to the

longitudinal axis of the connecting member 60 to coöperate with the integral adjusting means to adjust the trolley to different sized tracks.

3. In a trolley, the combination of a plurality of side plates, traction means carried 65 by the side plates, a single connecting member connecting the side plates, parallel indentations on the single connecting member, and a locking member carried by the side plates adapted to coöperate with the parallel 70 indentations on the single connecting member, to adjust the side plates to and from each other for different width of tracks.

4. In a trolley the combination of a plurality of side plates, traction means carried 75 by the side plates, a single connecting member connecting the side plates, parallel indentations on the single connecting member, and a locking member carried by the side 80 plates adapted to coöperate with the parallel indentations on the single connecting member, to adjust the side plates to and from each other for different width of tracks and supporting means mounted on the single 85 connecting member.

5. In a trolley the combination of a plurality of side plates, traction wheels, a connecting member connecting the side plates, said connecting member being provided with 90 two or more series of substantially parallel indentations arranged staggered with relation to each other, and a locking member to coöperate with the indentations.

6. In a trolley the combination of a plurality of side plates, traction wheels, a connecting member connecting the side plates, said connecting member being provided with a series of parallel indentations and a locking screw carried by one of the side plates 100 to coöperate with the parallel indentations and to lock the side plates in any desired adjusted position.

7. In a trolley the combination of a plurality of side plates, traction wheels, a connecting member connecting the side plates, said connecting member being provided with two or more series of substantially parallel indentations arranged staggered with relation to each other, and one or more locking 105 screws carried by the side plates adapted to coöperate with the parallel indentations to lock the side plates in any desired adjusted position.

ETHAN N. HESCOCK.
